UNITED STATES PATENT OFFICE.

HAROLD LICHTEN, OF PHILADELPHIA, PENNSYLVANIA.

STOCKING LEG.

Application filed March 10, 1924. Serial No. 697,994.

To all whom it may concern:

Be it known that I, HAROLD LICHTEN, a citizen of the United States, and a resident of the city of Philadelphia, county of Philadelphia, State of Pennsylvania, have invented certain new and useful Improvements in Stocking Legs, of which the following is a specification.

The present invention relates to the manufacture of stockings and more particularly to a method of making a stocking leg consisting in part of circular or seamless knitting and in part of flat or full fashioned knitting. More specifically the invention relates to the type of stocking shown in the patent to John Hadfield, Jr., No. 1,444,684, dated February 6, 1923, wherein the top of a stocking is knit on a circular knitting machine, then removed from such circular machine and transferred to a machine for continuing the knitting of the leg by the full fashioned method, which is nothing more than a form of the well-known "topping on" operation. Under the aforesaid patent, it is necessary to employ skilled operators to carry out the required intricate and exacting operation of transferring the end course of the circular knit fabric on to the needles of the full fashioned machine. This step consumes considerable time and while being carried out the expensive full fashioned machine is idle.

It is an object of the present invention to overcome the foregoing disadvantages of the Hadfield method by eliminating the need for experienced, high salaried help and loss of time by idle machines; further objects of the present invention are to provide a strong durable stocking formed by a combination of circular knitting and full fashioned knitting; to provide a method of forming a stocking leg embodying two separate and distinct knitting operations carried out either separately or simultaneously and without the necessity of the machine of either operation remaining idle; to provide a method of making a stocking leg in part by circular knitting and in part by full fashioned knitting whereby costs of manufacture are reduced, and increased production assured; and to provide other improvements as will hereinafter appear.

In the accompanying drawings, Fig. 1 represents a stocking top or upper portion of a stocking leg formed as a circular or seamless fabric; Fig. 2 represents the same

split longitudinally and spread flat; Fig. 3 represents a lower portion of a stocking leg formed as a flat or full fashioned fabric; Fig. 4 represents the lower leg portion of the stocking with the foot formed thereon; Fig. 5 represents the stocking top and leg portion seamed together end to end; and Fig. 6 represents a modified form of stocking top to which the invention is applicable.

Referring to the drawings, one form of the present invention consists in separately knitting a stocking top 10 and a stocking leg 11, the two being knit by different, separate and distinct knitting operations, and thereafter joining the two completed portions, as will be explained.

The stocking top 10, which consists of the welt and knee portion, is formed as a circular or seamless fabric and is preferably knit on a circular knitting machine until it is the desired or usual length of the upper portion of a stocking leg, and since under the present invention this top is formed entirely separate from the knitting of the leg and upon a different type of machine, the machine can be continuously operated and produce as many tops as are required. While the seamless type of machine is forming the fabric of the top 10, a machine of another type, preferably a full fashioned machine, is forming the stocking leg portion 11, which is a flat fabric, so that this machine can also be operated continuously to turn out as many leg portions as are required.

It is these two separately formed fabrics that form the complete leg of the stocking when they are properly joined together, and it is immaterial, in so far as the present invention is concerned, whether the top 10 is a fabric with a double thickness welt 12 or a welt of single thickness which may be turned to provide the double thickness welt of commercial form.

To unite the top portion 10 to the leg portion 11 the seamless fabric of the top 10 is cut longitudinally on a line 14, which is generally indicated by a suitable means, such for example as the dropping of a stitch at the same place in the successive courses of the fabric. The top 10 is now spread flat, and, as it has been designed to have the same flat width as the width of the leg to which it is to be attached, the lower end course will match the upper end course of the leg portion 11. These two end courses

are now brought together in a machine known as a looper, and thereby permanently sewn together with a lock stitch which prevents running and raveling, and produces 5 a neat, inconspicuous seam 15.

Following the foregoing step the incomplete stocking is folded to bring its two longitudinal edges together so that the toe, heel and back of the leg are joined together 10 by a seam 16 to form the complete stocking as shown in Fig. 5.

While broadly the present invention relates to a stocking leg to which a foot, a strap or any other holding means for the 15 bottom end can be knit or otherwise attached, it will be more generally employed with an ordinary knit foot 13 to form a stocking of the usual kind. This foot 13 is knit on a footer to which the leg portion 11 has 20 been transferred, and if the foot is knit to the leg 11 before its attachment to the top or upper portion 10, the appearance will be as shown in Fig. 4.

In Fig. 6 another embodiment of the invention is shown wherein a stocking top 17 is shown corresponding in all essentials to the fabric of Fig. 1, but instead of having an unbroken circular shape it is formed on a reciprocating type of circular knitting 30 machine which produces a fabric divided longitudinally as shown at 18 and having the two opposed margins finished respectively with selvages 20 and 21. By employing a machine which produces a fabric of 35 this type, the step of cutting or splitting the fabric is eliminated and the fabric is at once in shape to spread flat in matching relation with the lower flat leg portion 11.

It will now be apparent that a method 40 of making a stocking has been devised which greatly increases production, is cheaper to manufacture, and has all the desirable features of appearance and qualities of long 45 wear. By the present method it is unnecessary to transfer one knit portion from one machine to another of a different type to complete the stocking, and thereby loss of time and production caused by idle machines are eliminated. Attention is also directed 50 to the fact that the present method lends itself to flexible control of production because the steps of the method are subject

to optional variations without departing from the invention. Thus, for example, should a footing machine be temporarily out 55 of commission there need be no time lost in the method because during such interval the completed leg portion 11 can be sent direct to the seaming or looping machines to be joined to the top portion 10 and there- 60 after returned to the footer for knitting a foot thereon. It is preferred, however, to carry out the present method by knitting the foot to the leg prior to the attaching of the top to the leg because it has the ad- 65 vantage of more nearly insuring a matching of the leg fabric with the foot fabric. Thus where the legs go directly to the footer the probabilities are in favor of the silk or thread being from the same case and therefore require no change in the needle setting 70 to give the same appearance to both leg and foot fabrics.

Having thus described my invention, I 75 claim:

1. The method of making a stocking leg which consists in circular knitting the top or upper portion of the leg to form a circular seamless fabric, separately knitting the lower leg portion flat by full fashion 80 knitting, slitting said seamless fabric longitudinally and spreading it flat, looping the two portions together in end to end relation to form an open stocking leg, folding said open leg lengthwise, and seaming the meeting edges throughout the length of the joined leg portions.

2. The method of making a stocking leg which consists in knitting the lower portion of the leg as a flat fabric by full fashion 90 knitting, circular knitting the upper portion of the leg to form a tubular web half as wide as said flat fabric, cutting said web longitudinally and spreading flat in end to end relation to said flat fabric, looping the 95 two portions together to form an open stocking leg, folding said open leg lengthwise, and seaming the meeting edges throughout the length of the joined leg portion.

Signed at Philadelphia, in the county of 100 Philadelphia, and State of Pennsylvania, this 5th day of March, 1924.

HAROLD LICHTEN.
